Patented Mar. 14, 1916.

UNITED STATES PATENT OFFICE.

RICHARD LESLIE BIRKIN, OF NOTTINGHAM, ENGLAND.

DESIGN FOR LEVERS LACE.

48,705.

Specification for Design.

Patented Mar. 14, 1916.

Application filed January 17, 1916. Serial No. 72,642. Term of patent 3½ years.

To all whom it may concern:

Be it known that I, RICHARD LESLIE BIRKIN, a subject of the King of Great Britain and Ireland and the Isle of Man, and a resident of Nottingham, Nottinghamshire, England, have invented a certain new, original, and ornamental Design for Levers lace, of which the following is a specification, reference being had to the accompanying drawing, forming part thereof, in which the fig-

ure is a plan view of a portion of Levers lace, showing my new design.

I claim:

The ornamental design for Levers lace as shown.

RICHARD LESLIE BIRKIN.

Witnesses:

MARJORIE G. ROLLIN,

THOS. N. COOK.
